UNITED STATES PATENT OFFICE.

STEFAN WIESTER, OF BEAVER DAM, WISCONSIN, ASSIGNOR OF ONE-HALF TO RUDOLPH WEIMER, OF SHEBOYGAN, WISCONSIN.

ENAMEL-OVEN.

1,285,862.

Specification of Letters Patent. Patented Nov. 26, 1918.

Application filed October 5, 1917. Serial No. 124,917.

To all whom it may concern:

Be it known that I, STEFAN WIESTER, a citizen of the United States, and resident of Beaver Dam, in the county of Dodge and State of Wisconsin, have invented new and useful Improvements in Enamel-Ovens, of which the following is a description, reference being had to the accompanying drawings, which are a part of this specification.

10 The invention relates to improvements in enamel ovens.

Enamel ovens now in general use are provided with inside linings or muffles of tiles to prevent the ware placed within the oven from coming in direct contact with the injurious fire, gas, smoke, etc., of the furnace. The linings or muffles have bottom, side and arch portions usually built upon each other so that if any tile or portion of the different sections gives way or is defective in any manner it is necessary to tear down and rebuild the whole lining or muffle to replace a single part. This is an expensive proposition due to the high cost of material and the skilled labor required to rebuild the part and furthermore due to the liability of injury of additional parts in rebuilding.

It is one of the objects of the present invention to overcome the before mentioned objectionable features and provide an enamel oven in which the lining or muffle thereof is so constructed that any one tile or defective part may be easily replaced or repaired without disturbing other adjacent parts.

A further object of the invention is to provide an enamel oven in which the lining or muffle is formed of different sections, independent of each other which may be easily repaired or replaced without disturbing the other sections.

A further object of the invention is to provide an enamel oven in which the lining or muffle sections are independently supported upon projecting side wall portions and may be easily removed and replaced without injury to the other sections.

A further object of the invention is to provide an enamel oven which is of simple construction, is strong and durable and is well adapted for the purpose desired.

With the above and other objects in view the invention consists of the improved enamel oven and its parts and combinations as

set forth in the claims, and all equivalents thereof.

In the accompanying drawing in which the same reference characters indicate the same parts in all of the views:

Figure 1 is an end view of the improved enamel oven with the front plate portion removed;

Fig. 2 is a horizontal sectional view thereof taken on line 2—2 of Fig. 1; and

Fig. 3 is a vertical sectional view thereof taken on line 3—3 of Fig. 1.

Referring to the drawing the numeral 5 indicates the bottom wall, 6 the side walls, 7 the top wall or arch, 8 the rear end wall and 9 the front plate of the improved oven built in greater part of brick to form an inclosing space 10. The side walls 6 are built to form inwardly projecting and longitudinally extending partition ledges or supports 11 and 11' for independently supporting the side sections 12 and the arch or top sections 13 of the muffle wall of the oven. The lower ledges 11' are built solid from the bottom wall 5 and extend inwardly toward each other a greater distance than the other ledges to form longitudinally extending angular shoulders 14 for supporting the side edges of the lower muffle arch sections 15. These solid portions and the sections 15 form the fire or heater chamber 16 which communicates with the heating flues 17 and 18 formed between the ledges and the muffle sections and the outer walls of the oven. The upper flue 18 communicates with the chimney flue.

The upper edge portions of the ledges 90 are formed with longitudinally extending grooves 19 to receive the longitudinally extending tongues 20 formed on the lower edge portions of the wall sections 12 and the arch sections 13. The upper edges of the side sections fit beneath portions of the ledges 11 and against shoulders 21 formed on said ledges. The upper and lower arch sections are also formed with tongue and groove connections 22 between the parts, and the opposite side edge portions of the upper arch are formed with downwardly extending shoulders or flanges 23 which bear against the inner edges of the upper ledges 11.

It is to be understood that the ovens may be built in height of as many sections as desired, only two being shown in the drawing.

As each section is independently sup-

ported, in the event of injury to any of the members of one section, it will be only necessary to remove the broken part and slide a new part in place without in any manner disturbing the other sections.

From the foregoing description it will be seen that the enamel oven is of very simple construction and is well adapted for the purpose described.

10 What I claim as my invention is:

1. An oven, comprising outer oven walls having inwardly and horizontally extending reinforced supporting ledges, said reinforced ledges formed of a plurality of superposed courses of brick, some of said ledges positioned one above another, and inner lining sections removably supported on and between said ledges.

2. An oven, comprising outer oven walls having inwardly and horizontally extending reinforced supporting ledges, said reinforced ledges formed of a plurality of superposed courses of brick extending in stepped formation, and inner lining sections removably supported on said sections, there being a tongue and groove connection between the lining sections and the ledges.

3. An oven, comprising outer oven walls having inwardly and horizontally extending reinforced ledges, said reinforced ledges formed of a plurality of superposed courses of brick extending in stepped formation, some of said ledges positioned one above the other, inner lining arch sections removably supported on some of said ledges, and inner lining side sections supported on and between some of said ledges, there being a tongue and groove connection between the arch and the side sections and the ledges.

4. An oven, comprising outer oven side walls having inwardly and horizontally extending reinforced ledges, said reinforced ledges formed of a plurality of superposed courses of brick extending in stepped formation, some of said ledges positioned one above the other, inner lining upper arch

sections removably supported on the upper ledges, inner lining side sections supported on other of said ledges and between the said ledges, and inner lining lower arch sections 50 removably supported on the lower ledges, there being a tongue and groove connection between some of the inner lining sections and the ledges, said side walls and arches and side lining sections forming a plurality 55 of flues between the outer walls and the lining sections.

5. An oven, comprising outer oven side walls having inwardly and horizontally extending reinforced ledges, said reinforced 60 ledges formed of a plurality of superposed courses of brick extending inwardly in stepped formation, some of said ledges positioned one above the other, inner lining upper arch sections removably supported 65 on the upper ledges and having downwardly extending flanges which engage the ledges, inner lining sections supported on other of said ledges and between the said ledges, and inner lining lower arch sections removably 70 supported on the lower ledges, there being a tongue and groove connection between some of the inner lining sections and the ledges, said side walls and arches and side lining sections forming a plurality of flues 75 between the outer walls and the lining sections.

6. An oven, comprising outer oven walls having inwardly and horizontally extending reinforced ledges, said reinforced ledges 80 formed of a plurality of superposed courses of brick extending inwardly in stepped formation, some of said ledges positioned one above the other, inner lining arch sections removably supported on some of said ledges, 85 and inner lining side sections supported on and between some of said ledges, there being a tongue and groove and a shouldered connection between the arch and the side sections and the ledges.

In testimony whereof, I affix my signature.
STEFAN WIESTER.
